OF BUFFALO, NEW YORK, A CORPORATION OF NEW YORK.

PIANO-LAMP.

1,361,241.

Specification of Letters Patent.

Patented Dec. 7, 1920.

Application filed February 23, 1918. Serial No. 218,611.

To all whom it may concern:

Be it known that I, ALLAN FRASER, a citizen of the United States, residing in Buffalo, in the county of Erie and State of New York, have invented new and useful Improvements in Piano-Lamps, of which the following is a specification.

This invention relates to a lamp which is more particularly designed for illuminating the space in front of a piano so that the key board and music are clearly visible and it has for its object the production of a lamp of this character which is comparatively simple and inexpensive in construction, 15 which can be easily and conveniently applied to the fronts of upright pianos which may vary in thickness and construction, and which is neat and ornamental so as not to detract from the appearance of the piano 20 upon which the same is mounted.

In the accompanying drawings: Figure 1 is a fragmentary vertical section of a piano front and lid showing my improved lamp applied thereto. Fig. 2 is a top plan view 25 of the same with the lid omitted and the hood of the lamp shown partly, in section. Fig. 3 is a perspective view of the lamp viewed from its under side and showing the lighting element omitted. Fig. 4 is a fragmentary vertical section, on an enlarged scale, taken on line 4—4, Fig. 2.

Similar characters of reference indicate corresponding parts throughout the several views.

Although this lamp may be applied to pianos which may vary in construction the same is shown in Fig. 1 applied to an upright piano the casing of which has an upright front or board 1 which can be tilted 40 more or less in order to support the music thereon in a more or less inclined position and a normally horizontal lid or top 2 which is movable vertically toward and from the front board.

The piano lamp which embodies my improvements is adapted to be mounted upon the upper edge of the piano front and below the lid and in its preferred form the same is constructed as follows:

The front of the lamp has the form of a hood which is preferably constructed of sheet metal and comprises a cylindrical body 3 which is normally arranged horizontally and provided in its underside with a longitudinal light outlet opening 4 and two cir-

cular heads 5, 6 applied to opposite ends of this body. Arranged lengthwise within the hood is the lighting element which in this instance consists of an electric light bulb 7 which is detachably connected with a socket 8 arranged within the hood and mounted on one of the heads of the hood, for instance the head 5 at the left hand end of the same. The cord 9 containing the electric conducting wires for the lamp filament is 65 preferably extended laterally through one side of the head 5, and the socket 8 is provided with an internal switch for opening and closing the circuit of this lamp which switch may be controlled by means of a pull 70 chain 10 connected with the switch in any suitable and well known manner.

My improvements relate more particularly to the mounting whereby this hood is detachably supported on the piano front and the heat of the electric bulb is prevented from being transmitted from the hood to the finished or varnished surfaces of this front so that scorching or marring of the same is avoided. In its preferred form this mounting is constructed as follows:

In rear of the hood is arranged a bracket which comprises two longitudinal front arms 11, 11 projecting rearwardly from the rear side of the hood and each provided at 85 its front end with a depending attaching or coupling lug 12, a cross piece 13 of substantially U-shaped form arranged in rear of said front arms and having the forwardly projecting branches at its opposite ends connected with the rear ends of the front arms and a longitudinal rear arm 14 projecting rearwardly from the central part of the cross piece and provided at its rear end with a downwardly projecting lug 15. The connection between the front part of the bracket and the hood may be accomplished in various ways but preferably by a bolt 16 passing through each attaching lug and the adjacent part of the hood, and a heat insulator 100 17 of fiber or other suitable material interposed between the attaching lug and the adjacent part of the hood so as to reduce to a minimum the metallic connection between the hood of the bracket and thereby avoid 105 undue transmission of the heat of the electric light bulb through the metallic parts of the bracket to the adjacent surfaces of the piano. This transmission of heat is further reduced by providing the front parts 110

of the bracket arms with openings 18 so as to allow air to pass through the same and keep them cool.

The rear parts of the front bracket arms 5 are bent upwardly at right angles to the front parts thereof so as to form outer jaws 19 which are adapted to face the outer or front side of the piano front while the cross piece of the bracket extends rearwardly over 10 the top of the piano front. In order to prevent marring the outer side of the piano front and the upper edge thereof facings 20 of felt or other suitable cushioning material are applied to the rear side of the 15 jaws 19 and the undersides of the cross piece 13 and rear arm which permits these parts to engage with the respective surfaces of the piano front without injuring or marring the same upon applying the lamp thereto. 20 The front and rear arms and the cross piece together with the front and rear lugs are preferably constructed of a single piece of sheet metal to simplify the construction and reduce the cost of manufacture.

25 21 represents a bow spring which is preferably constructed of flat resilient metal and secured with the central part by means of rivets 22 to the rear lug of the bracket so that the ends thereof project forwardly and 30 engage yieldingly with the inner side of the piano front. Owing to the resilience of these spring arms or ends the same are capable of adapting themselves to piano fronts which vary in thickness, thereby permitting 35 of universal application of this lamp to pianos having an upright front board or any other piano having an upright member capable of receiving this mounting.

The bow spring which forms a flexible jaw 40 for engaging with the rear or inner side of the piano front has its flat sides arranged vertically and the same extends horizontally and transversely with reference to the bracket as a whole, so that when this spring 45 engages with the rear side of the piano front the same will not project downwardly into the space within the piano case where the same would be liable to interfere with the mechanism therein.

50 In applying this lamp to a piano it is only necessary to spread the ends of the bow spring apart sufficiently to permit of engaging the front jaws with the outer side of the piano front and the ends of the spring with 55 the inner side of this front after which the resilience of this spring exerts a sufficient grip upon the piano front to hold the lamp reliably in place. The mounting of the lamp

on the piano front as well as the removal thereof can be effected easily and conveniently without requiring any tools and when mounted the same permits of closing the lid upon the bracket and the piano front so that the top of the piano can be used in the ordinary manner if desired. Owing to the compact and neat construction of this lamp the same when mounted on a piano does not detract from the appearance of the piano but rather enhances the same.

I claim as my invention:

1. A piano lamp comprising a hood adapted to receive an electric bulb and provided on its underside with a light outlet, and means for supporting said hood on a piano front comprising a bracket connected with the 75 hood and adapted to engage with the outer side of the piano front, and a horizontally and transversely arranged bow spring mounted with its central part on said bracket and adapted to engage its opposite 80 ends with the inner side of the piano front.

2. A piano lamp comprising a hood adapted to receive an electric bulb and provided on its underside with a light outlet, and means for supporting said hood on a 85 piano front comprising a bracket having two front arms connected with the hood and adapted to bear against the outer side of the piano front, a cross piece connecting said front arms and extending over the piano front and a rear arm projecting rearwardly from the central part of said cross piece, and a spring arranged on said rear arm and adapted to engage with the inner 90 side of the piano front.

3. A piano lamp comprising a hood adapted to receive an electric bulb and provided on its underside with a light outlet, and means for supporting said hood on a piano front comprising a bracket having 100 two spaced front arms which are connected at their front ends with the rear side of said hood and which are provided at their rear ends with upwardly projecting jaws adapted to engage with the outer side of the piano front, a U-shaped cross piece having its ends connected with said jaws and adapted to extend rearwardly over the top of the piano front and a rear arm extending rearwardly from the central part of said cross piece and provided at its rear end with a downwardly projecting lug, and a bow spring secured with its central part to said lug and adapted to engage its opposite 110 ends with the inner side of the piano front.

ALLAN FRASER.
